UNITED STATES PATENT OFFICE.

EDWARD MASTER, OF NEOSHO, SASKATCHEWAN, CANADA.

SAND-POINT FOR WELL-DRILLING.

1,288,100.

Specification of Letters Patent. Patented Dec. 17, 1918.

Application filed April 30, 1917. Serial No. 165,494.

To all whom it may concern:

Be it known that I, EDWARD MASTER, a subject of the King of England, residing at Neosho, Province of Saskatchewan, Dominion of Canada, have invented new and useful Improvements in Sand-Points for Well-Drilling, of which the following is a specification.

The invention relates to a driving well point, and more particularly to the class of sand points for use in well drilling.

The primary object of the invention is the provision of a point of this character wherein the same is prevented from clogging when in use and also from breaking or becoming damaged when driven into the earth or withdrawn therefrom and in event of damage can be readily repaired expeditiously, thereby eliminating the necessity of an entirely new point.

Another object of the invention is the provision of a point of this character wherein the construction thereof is novel in form to assure longevity in the use thereof and that will withstand the work without possibility of clogging.

A further object of the invention is the provision of a point of this character which is extremely simple in construction, thoroughly reliable and efficient in its purpose, strong, durable and inexpensive in manufacture.

Other objects will be in part obvious and in part hereinafter set forth.

The invention accordingly consists in the features of construction, combination of elements and arrangements of parts which will be exemplified in the construction herein-after described, and the scope of the application of which will be indicated in the appended claim.

In the drawings:

Figure 1 is a side elevation of a point constructed in accordance with the invention;

Fig. 2 is a vertical longitudinal sectional view thereof;

Fig. 3 is a perspective view of one of the guard bars; and

Fig. 4 is an enlarged longitudinal transverse sectional view.

Similar reference characters indicate corresponding parts throughout the several views of the drawing.

Referring to the drawing in detail, A designates generally the tube or cylinder 55 and B the piercing tip or plug of the sand point which is integral with or mounted in the tube or cylinder at one end thereof, the mounting being effected in any suitable manner, and this tube or cylinder B is 60 formed with a series of rows of perforations or holes C, while exteriorly of and concentrically disposed with respect to said tube or cylinder A are spaced parallel bars 5, each being preferably made from soft steel and 65 is of tapered formation in cross section throughout a major portion of its length, having offset anchoring terminals 6 which engage in suitable openings 7 formed in the said tube or cylinder A for the mounting of 70 the bar thereon longitudinally of the same.

Formed at intervals on the bar at one side are lugs or ears 8, while in the opposite side are recesses 8' for the lugs or ears so that the bars will be held interlocked with each other and spaced apart. In suitable grooves formed in the outer faces of the bars and lugs or ears are engaged retaining wires 9, the ends of each being spliced at 10 with respect to a bar 11 which is identical to the 80 bars 5 with the exception that the same is slightly wider than said bars 5, and in this manner the companion bars of the series are held securely in their separated relation to each other about the tube or cylinder B so 85 as to prevent the clogging of the point in the use thereof for well drilling.

The bars 5 provide therebetween spaces which are tapered from the outside inwardly, and these bars prevent the possibility of the clogging of the point when working in coarse or fine sand. The point is capable of being driven and there is no possibility of the clogging thereof when in use or the breaking or tearing of the same 95 when being driven or removed in drilling a well.

From the foregoing description, taken in connection with the accompanying drawing, the construction and operation of the 100 herein described sand point will be readily apparent and, therefore, a more extended explanation has been omitted.

Having thus described my invention, I claim:

A point of the character described com-

prising a perforated tube having a pointed
trip, a plurality of bars concentrically of the
tube, each bar being tapered in cross section
for a major portion of its length, anchor-
5 ing terminals on the bars and engaged in
the tube, ears at one longer edge of each
bar and adapted for interlocking engage-

ment with an adjacent bar, and retaining
means surrounding the bars at the points of
the ears and lying flush with the outer faces 10
of said bars.

In testimony whereof I affix my signature.

EDWARD MASTER.
